CLAIM

I claim the ornamental design for a bin, as shown and described.

DESCRIPTION

FIG. 1 is a front/left/top perspective view of a bin (the front/right/top perspective view being a mirror image thereof);

FIG. 2 is a rear/right/bottom perspective view thereof (the rear/left/bottom perspective view being a mirror image thereof);

FIG. 3 is a front elevational view thereof (the rear elevational view being a mirror image thereof);

FIG. 4 is a right side elevational view thereof (the left side being a mirror image thereof);

FIG. 5 is a top plan view thereof; and,

FIG. 6 is a bottom plan view thereof.

The broken lines represent portions of the bin (bin openings, the bottom, and lines where surfaces meet) that form no part of the claimed design. Some broken line features that would be visible behind the transparent surfaces in FIGS. 1 and 2 are omitted for a clear disclosure of the interior surface configuration. Actual appearance of exterior surfaces is as set forth in elevational views.

1 Claim, 4 Drawing Sheets
